(57) **CLAIM**

The ornamental design for a lice comb, as shown and described.

DESCRIPTION

FIG. 1 is a front perspective view of a lice comb showing my new design.

FIG. 2 is a back perspective view of the lice comb.

FIG. 3 is a front view of the lice comb.

FIG. 4 is a back view of the lice comb.

FIG. 5 is a right side view of the lice comb; the left side view is a mirror image of the right side view and is not shown.

FIG. 6 is a cross-sectional view of the lice comb taken along line 6-6 in FIG. 3.

FIG. 7 is a top view of the lice comb.

FIG. 8 is a bottom view of the lice comb.

FIG. 9 is a cross-sectional view of the lice comb taken along line 9-9 in FIG. 3; and,

FIG. 10 is a cross-sectional view of the lice comb taken along line 10-10 in FIG. 3.

The broken lines in the figures are for the purpose of illustrating portions of the lice comb, which form no part of the claimed design.

1 Claim, 3 Drawing Sheets
